DOLL

Winifred W. Hill and Opal A. Johnson,
Redwood City, Calif.

Application August 2, 1949, Serial No. 4,244

Term of patent 3½ years

(Cl. D34—4)

To all whom it may concern:

Be it known that we, Opal A. Johnson and Winifred W. Hill, citizens of the United States of America, residing at Redwood City, in the county of San Mateo and State of California, have invented a new, original, and ornamental Design for a Doll, of which the following is a specification, reference being had to the accompanying drawing, forming a part thereof.

Fig. 1 is a front elevational view of a doll, showing our new design, and

Fig. 2 is a side elevational view of the same.

We claim:

The ornamental design for a doll, substantially as shown.

WINIFRED W. HILL.
OPAL A. JOHNSON.
